UNITED STATES PATENT OFFICE

GEORGE T. HUXFORD, OF PROVIDENCE, RHODE ISLAND

APPARATUS FOR DRYING, SPECIFICALLY IRONING

Application filed April 19, 1928. Serial No. 271,304.

My invention relates to an improved apparatus for drying. While my invention may be applied to any type of drying in textile, paper-making, or other industries, particularly in machines employing the general type of rolls known as calendering rolls, it specifically relates to the general type of ironing machines having an undulating ironing bed and a plurality of perforated cylindrical drying rolls mounted within the undulations of said ironing bed in offset relationship thereto such as is shown for instance in Patent No. 1,432,940 issued Oct. 24, 1922, to Thomas J. Yates.

A feature of my invention consists in discharging air, preheated to increase its moisture absorbing capacity, under pressure outwards through a perforated drying member. It is well-known that heating air makes it capable of absorbing more moisture and thereby increases its drying efficiency, but so far as I am aware no one has hitherto applied this principle in drying machinery. While I am aware that others have created a vacuum with the interior of a hollow drying member to suck air in through the perforated drying surface thereof, so far as I am aware no one has hitherto blown or circulated preheated air out through a perforated drying surface. This air circulation may be produced by positive pressure or negative vacuum pressure, or by both. By the pressure method, air from anywhere, preferably out of doors, is forced into the rolls, and thence after heating thoroughly, the padding. By the vacuum method, one or more suction blowers create a partial vacuum in the room, (thus exhausting the moisture previously extracted from the clothes), while the insides of the rolls are connected with an air supply from outside of the room. A further object of my invention, therefore, is to provide suction means to not only draw the preheated air out through the rolls or other members employed, but also to simultaneously exhaust the room of preheated air. A further object of my invention is to provide a drying machine capable of carrying out this function. A further object of my invention

relates to a provision of a specific rotatable roll capable of carrying this out.

Where a steam coil is inserted within a rotatable drying roll a certain amount of water becomes condensed therein and a feature of my invention relates to the removal of condensed water from a rotating cylindrical roll and includes passing the steam axially into the member in a confined helical path, whereby the inertia of the condensed water or gravity or both may on revolution of the roll cause its own discharge through a suitable discharge duct. A feature of my invention therefore specifically relates to a drying roll having convoluted steam coils therein capable of this discharge of condensed water.

These and such other objects of my invention as may hereinafter appear will be best understood from a description of the accompanying drawings which illustrate an embodiment thereof applied to an ironing machine.

In the drawings, Fig. 1 is a diagrammatic sectional view of an undulating bed ironing machine of a standard type adapted to iron a stream of clothes.

Fig. 2 is a longitudinal sectional view of my preferred type of invention with the steam coil arranged in helical convolutions within a roll, partially shown in elevation.

Fig. 3 is a longitudinal sectional view of an embodiment of my invention differing in certain slight features from the embodiment of my invention shown in Fig. 2, partially shown in elevation.

In the drawings, wherein like characters of reference indicate like parts throughout, 10 generally indicates the undulating horizontal drying bed of a standard type of ironing machine having the spaced undulations 12 therein, the ironing bed being normally hollow and filled with steam. 14 generally indicates a plurality of perforated cylindrical drying rolls mounted transversely of the machine within the undulations 12 of said drying bed in slightly offset relationship thereto. The rolls 14 are slightly offset from the bed 10 in order to provide a passage-way 16 for the clothes to be ironed between the rotating rolls and the stationary undulating 180

bed 10. Means are provided to rotate said rolls. A continuous stream of clothes is adapted to be inserted at the front end 18 of the undulating passage-way 16 and passed by 5 rotation of the rolls through the undulating passage-way 16, being discharged at the opposite end 20 of said passage-way and machine in ironed condition.

As shown in Figs. 2 and 3 the rolls 14 are 10 preferably radially perforated as shown at 22 and are provided with the flexible pervious covering 24 constructed of suitable material to permit a passage of air radially outwards therethrough. As stated previously, 15 my invention broadly consists in passing material to be dried across the pervious drying surface of a drying member and circulating air under pressure preheated to increase its moisture absorbing capacity outwards 20 through the member, whereby the preheated air may penetrate the material to be dried and take away a relatively greater amount of moisture therefrom. In my preferred embodiment the drying members having perforated 25 drying surfaces comprise the rolls 14 provided with the drying surfaces 26, which comprise the cylindrical surfaces of the rolls 14 having the perforations 22 therein. I provide means to discharge air under 30 pressure outwards preferably radially through the perforated drying surfaces 26 and thus into contact with the material to be dried or ironed, said means may comprise a blower (not shown) suitably connected by 35 means of a suitable pipe 28 to the interior 30 of the perforated drying roll 14. I also provide in combination therewith means to preheat said air before said discharge to increase its moisture absorbing capacity. This drying 40 action of the air and of the radiant heat from the steam coil is not confined to the clothes, nor is its major benefit secured directly. It causes the padding through which it passes to be rapidly dried during that portion 45 of its revolution when it is not in contact with the clothes, thus making it (the padding) much more absorbent while in contact with the clothes. In my preferred embodiment said means comprises the steam coil 34' 50 or 34" preferably contained within the interior 30 of the roll and connected to the steam inlet pipe 36. As shown in Figs. 2 and 3 I provide the driving pulley 38 on the roll shaft for rotation thereof. In the embodiments shown in Figs. 2 and 3 I provide the hollow trunnions 40^a and 40^b adapted to be mounted in suitable bearings 42 in each end 55 of the roll 14 which form said roll shaft.

As stated, however, a feature of my invention relates to an improved apparatus and specific construction of steam coil which will automatically on rotation thereof through the inertia of the condensed water itself, as well as by gravity, cause a discharge thereof 60 and comprises an apparatus for discharging

condensed water from a steam heated rotatable member which comprises passing the steam axially through the drying member in a convoluted confined path whereby the inertia of the condensed water may on rotation of the member cause its own discharge. To this end as shown in Figs. 2 and 3 I preferably construct the steam coil in the form of a helical coil 34' contained within the hollow interior 30 of the roll adjacent the cylindrical wall 26 thereof. Figs. 2 and 3 specifically illustrate constructions of drying rolls capable of carrying out this feature of my invention. Each of the embodiments shown in Figs. 2 and 3 consists of a hollow rotatable perforated drying roll having a perforated cylindrical drying surface 26, hollow duct forming trunnions 40^a and 40^b at each end thereof and an additional substantially annular duct 44 at one end thereof having an enlarged annular passage-way 46 at the outer end thereof and a convoluted steam coil 34' or 34" respectively contained within said roll having the ends thereof connected to two of the three ducts 40^a, 40^b or 44.

In the embodiment shown in Fig. 2 the ends of the steam coil 34' are suitably connected to the hollow trunnions 40^a and 40^b, the steam inlet pipe 36 is connected to the hollow trunnion 40^b and an additional steam outlet pipe 48 is suitably connected to the opposite trunnion 40^a. The steam is thereby passed through the roll, through the steam inlet pipe 36, the hollow trunnion 40^b, and the helical coil 34' and out through the hollow trunnion 40^a and the steam discharge pipe 48. The air inlet pipe 28 is suitably connected to the annular portion 46 of the substantially annular duct 44 and is directly discharged into the interior 30 of the roll 14 through said annular duct 44.

In the embodiment shown in Fig. 3, however, the steam is admitted through the steam inlet pipe 36 connected to the hollow trunnion 40^b to which is connected the intake end of the steam coil 34". The outlet of the steam coil 34" however, is suitable connected to the substantially annular duct 44 which now becomes a discharge duct for the discharge of steam and condensed water from the coil 34" out through the medium of the enlarged annular duct 46 and discharge pipe 48. In the embodiment shown in Fig. 3 air is admitted through the air inlet pipe 28 connected to the hollow trunnion 40^a.

While both of the embodiments shown in Figs. 2 and 3 employ my improved principle of passing the steam axially through the member in a confined convoluted path, the embodiment shown in Fig. 2 is slightly more uniform in its heat transfer relationship. It is obvious that on rotation of the roll the water condensed in each convolution 50 of the coil will settle by the force of gravity in the bottom thereof and on continued revolution

tion of the coil will automatically travel towards the end of the coil to which the discharge pipe is attached and will automatically be ejected through the discharge pipe

5 48 on continued revolution of the roll.

In the embodiments hitherto described, air has been forced outwards by a pressure blower through the perforated drying surface of the drying member. It is obvious,

10 however, that this circulation may be caused by means of a negative pressure or a suction blower to suck the air outwards through said surface.

As it is thus apparent that as the air may be forced outwards through the drying surfaces 26 either by a blower under positive pressure or by a suction pump under negative pressure, I, therefore, employ the word pressure in the claim to signify either a positive

20 or a negative pressure.

In the claim I employ the word "perforated" to indicate any pervious drying surface which will permit the passage of air outwards therethrough. While I have shown my invention employed in connection with a multiple roll ironing machine, it is obvious that certain features thereof may be applied in any type of a drying member, preferably a roll used for drying purposes in

30 any industry.

It is understood that my invention is not limited to the specific embodiments shown or methods described and that various deviations may be made therefrom without departing from the spirit and scope of the appended

35 claim.

What I claim is:

In combination a hollow rotatable ironing machine roll having a substantially uniformly perforated cylindrical drying surface, an air duct to admit air under pressure to the interior of said roll and a helical steam coil contained within the hollow interior of said roll to preheat said air prior to its radial discharge through the perforated drying surface wound opposite the desired direction of revolution of said roll when viewed from the steam inlet end of the roll, and means to revolve said roll in a direction opposite to the

45 windings of said helical steam coil, whereby the inertia or gravity of the condensed water and steam may cause its discharge through the discharge end of the coil on revolution of the roll.

50 55 In testimony whereof I affix my signature.

GEORGE T. HUXFORD.
